ADJUSTABLE JACK

Filed April 16, 1928

UNITED STATES PATENT OFFICE

CORNELIUS G. BOUDETTE, OF CLAREMONT, NEW HAMPSHIRE, ASSIGNOR TO SULLIVAN
MACHINERY COMPANY, A CORPORATION OF MASSACHUSETTS

ADJUSTABLE JACK

Application filed April 16, 1928. Serial No. 270,456.

This invention relates to adjustable jacks and more particularly to an adjustable roof jack especially adapted to use in mines.

An object of this invention is to provide an improved adjustable jack. Another object is to provide an improved adjustable jack which may be set up and taken down quickly and with facility. Another object is to provide an improved adjustable jack having improved adjusting means of simple yet rugged construction and adapted to be manufactured at relatively small expense. These and other objects of this invention will, however, hereinafter more fully appear 15 as the description proceeds.

In the accompanying drawing there is shown for purposes of illustration one form which the invention may assume in practice.

In this drawing,—

Fig. 1 is a side elevational view of the improved adjustable jack, parts being omitted to facilitate illustration.

Fig. 2 is a longitudinally extending sectional view taken substantially on line 2—2 25 of Fig. 1.

Fig. 3 is a perspective view of one of the pawl adjusting levers.

Fig. 4 is a perspective view of one of the pawls.

Fig. 5 is an elevational view illustrating the jack set up in operative position in a mine.

In this illustrative construction there is shown a jack 1 comprising a main tubular body portion 2 carrying at its upper end a member 3 having pivotally connected thereto at 4 an adjustable abutment or support engaging member 5 having serrations on its upper surface adapted to engage suitable blocking or the mine roof. As shown, fixed as by rivets or other suitable attaching means adjacent the lower end of the tubular jack body 2 is a flanged collar or coupling 6, the flange of which rotatably supports a casing or housing 7. This housing has a central opening 8 within which the lower end of the jack body projects as shown in Fig. 2. Pivotally mounted on pins 9 carried by the housing 7 are pawls or dogs 10 engageable with helically formed teeth 11 on an

axially movable adjusting screw 12 extending through the central opening in the housing and telescopically arranged within the tubular jack body 2. This screw is provided at its outer or lower end with an abutment 55 engaging member or foot piece 13 having spaced points 14 for maintaining the adjusting screw 12 against rotative movement during adjustment of the jack. This foot piece is engageable with suitable blocking or the 60 mine floor.

As illustrated, arranged within the housing 7 are coil springs 15 acting on the pawls 10 for yieldably maintaining the latter in engagement with the teeth of the adjusting screw. Suitable adjustable plugs or followers 16 are threaded into the housing and are adjustable to vary the tension of the coil springs. In accordance with this invention the pins 9 also have pivotally mounted thereon levers 17 projecting laterally through openings 18 in the sides of the housing and having grasping portions 19. As clearly shown in Fig. 3 these levers 17 have lugs 20 projecting laterally from their hubs and 75 these lugs each have oppositely located abutment surfaces 21 and 22. The pawls 10 have similar abutment surfaces 23 and 24 formed by cutting away a portion of their bearing supports. It will thus be seen that when the 80 levers 17 are in the position indicated in full lines in Fig. 2 the abutment surfaces 21 on the levers are in engagement with the abutment surfaces 24 on the pawls 10, while when the levers are in the dotted line position in that 85 figure the surfaces 22 and 23 on the levers and pawls respectively are in engagement. It will further be seen that when the levers 17 are in the full line position shown in Fig. 2 and are pressed inwardly toward one another, the pawls may be swung outwardly from engagement with the teeth on the adjusting screw 12 thereby permitting the latter to slide freely relative to the tubular jack body.

In the use of the improved adjustable jack the operator first places the jack in the position shown in Fig. 5 and then presses inwardly on the levers 17 releasing the pawls 10 from engagement with the teeth on the ad-

justing screw 12 thereby permitting the latter to slide downwardly until the foot piece 13 engages the blocking or the mine floor, the levers thereafter being released and the 5 pawls automatically maintaining the jack in position. The operator then swings the levers 17 downwardly into the dotted line position shown in Fig. 2 and as shown in full lines in Fig. 5 and then bodily rotates the housing 7 relative to the tubular jack body thereby causing the pawls to act as a nut forcing the jack body and the adjusting screw axially apart and as a result the jack is rigidly held in position, the pawls preventing separation 15 between the adjusting screw and the jack body when the jack is so positioned. When it is desired to take down the jack the operator merely rotates the housing 7 thereby loosening the jack parts and thereafter releasing 20 the pawls from the adjusting screw permitting the latter to be slid inwardly within the jack body, the pawls maintaining the adjusting screw in its retracted position.

As a result of this invention it will be noted 25 that an improved adjustable jack is provided which may be adjusted expeditiously and with facility. It will further be noted that the adjusting means for the jack is composed of a relatively few parts which are of simple 30 yet rugged construction especially adapted to withstand the severe conditions of service and which may be manufactured at a minimum of expense. These and other uses and 35 advantages of this invention will be clearly apparent to those skilled in this art.

While I have in this application specifically described one form which my invention may assume in practice, it will be understood that this form is shown for purposes of illustration and that the invention may be modified and embodied in various other forms 40 without departing from its spirit or the scope of the appended claims.

What I claim as new and desire to secure 45 by Letters Patent is:

1. An adjustable jack comprising a body member carrying an abutment engaging member, a plurality of pawls carried by said body member, a helical screw arranged to telescope within said body member, spring means normally tending to hold said pawls in engagement with the threads on said helical screw, said pawls having means adapted to cooperate with said threads for effecting 50 relative longitudinal movement of said body member and screw upon rotation of said pawls around said screw, and handle means adjustable relative to said pawls and movable into one position to effect release of said pawls from said threads to permit free collapsing of said jack, said handle means also being adjustable to another position wherein they project laterally to serve as leverage attaining means for rotating said pawls 55 around said screw.

2. An adjustable jack comprising a tubular body, a helical screw telescoping therewith, a pair of pawls pivotally carried by said body, spring means normally tending to hold said pawls in engagement with the threads on said helical screw, and a pair of handle members having a lost motion connection with said pawls adapted when swung toward said body member to engage said pawls and to move them out of engagement with said threads to permit free collapsing of said jack, said lost motion connection permitting said handle members to be swung to a position substantially at right angles to said screw to serve as means whereby the pawls may be rotated about said screw to effect adjustment of said jack.

3. An adjustable jack comprising a tubular body carrying an abutment engaging member, a helical screw telescoping therewith, a housing rotatably connected to said body member and surrounding said screw, a pair of pawls pivotally carried in said housing, a pair of springs acting on said pawls normally tending to hold them in engagement with the threads on said helical screw whereby rotation of said housing and pawls around said screw will effect adjustment of said jack, and a pair of handle members pivotally mounted on the same axis as said pawls and having a lost motion connection therewith whereby they may be moved to one position to effect release of the pawls from said threads and to another position at right angles to said screw to serve as means for rotating the housing and pawls.

4. An adjustable jack comprising a tubular body member carrying abutment engaging means, a helical screw arranged to telescope within said body member, adjustable elements adapted to engage with the threads on said screw for effecting relative longitudinal adjustment between said body member and screw upon rotation of said elements around said screw, and handle means for adjusting said thread engaging elements and movable into one position to effect release of said thread engaging elements and into another position to provide lever means for rotating said thread engaging elements around said screw, said handle means in said last mentioned position permitting engagement of said thread engaging elements with the threads of said screw.

5. An adjustable jack comprising a hollow body member carrying an abutment engaging means, a support rotatably mounted on said body member, a helical screw arranged to telescope within said body member, elements adjustably mounted on said rotatable support and movable into and out of engagement with the threads on said screw, and handle means adjustably mounted on said support and adjustable into a position for moving said thread engaging elements out

of engagement with said threads to permit free collapsing of the jack, said handle means also being adjustable into a position to move said thread engaging elements into engagement with said threads, said handle means being operative to effect rotation of said support relative to said body member to move said thread engaging elements about said screw to effect relative longitudinal adjustment of the body member and screw.

6. An adjustable jack comprising a hollow body member carrying an abutment engaging means, a support rotatably mounted on said body member, a helical screw arranged to telescope within said body member, pawls carried by said rotatable support and engageable with the threads of said helical screw, said pawls being adapted to cooperate with said threads for effecting relative longitudinal movement of said body member and screw upon rotation of said support relative to said body member, said support being rotatable to effect movement of said pawls around said screw, and handle means for releasing said pawls from engagement with said threads to permit free collapsing of said jack and for rotating said support relative to said body member to effect rotation of said pawls around said screw.

7. An adjustable jack comprising a hollow body member, a support rotatably mounted on said body member, a helical screw arranged to telescope within said body member, pawls pivotally mounted on said rotatable support and adapted to cooperate with the threads of said helical screw, and means for rotating said support relative to said body member to effect movement of said pawls around said screw for adjusting said screw longitudinally relative to said body member including handle members pivotally connected to said support about axes coincident with the pawl axes and swingable relative to said pawls, said handle members also being operative to effect release of said pawls from engagement with the threads of said screw to permit free collapsing of said jack.

8. An adjustable roof jack comprising a tubular body member, an adjusting screw telescopically received in said body member, said body member and screw having abutment engaging members normally preventing rotation of said body member and screw when the jack is in operative position, and means for effecting relative axial adjustment of said body member and screw to move said abutment engaging members apart to position the jack, and including a rotatable member carried by said body member, an element carried by and adjustable relative to said rotatable member and forming a nut engageable with the threads of said screw, and means for adjusting said nut forming element into and out of its thread engaging position while said screw remains stationary with re-

spect thereto, and for rotating said rotatable member relative to said body member when said nut forming element is in its thread engaging position to effect relative axial adjustment of said body member and screw, said screw and body member when said nut forming element is released from the threads of said screw having free telescopic movement to permit collapsing of the jack.

9. An adjustable roof jack comprising a tubular body member, an adjusting screw telescopically received in said body member, said body member and screw having abutment engaging members normally preventing rotation of said body member and screw when the jack is in operative position, and means for effecting relative axial adjustment of said body member and screw to move said abutment engaging members apart to position the jack, and including a rotatable member carried by said body member, an element carried by and adjustable relative to said rotatable member and forming a nut engageable with the threads of said screw, and means for adjusting said nut forming element into and out of its thread engaging position while said screw remains stationary with respect thereto, and for rotating said rotatable member relative to said body member when said nut forming element is in its thread engaging position to effect relative axial adjustment of said body member and screw, said screw and body member when said nut forming element is released from the threads of said screw having free telescopic movement to permit collapsing of the jack, and said nut forming element engaging the threads of said screw to form a lock to hold said screw in its collapsed position.

In testimony whereof I affix my signature. 105
